US00D692906S

(12) **United States Design Patent**
Coudron

(10) **Patent No.:** **US D692,906 S**
(45) **Date of Patent:** **** Nov. 5, 2013**

(54) **TAB AREA SEARCH TOOL FOR DISPLAY SCREEN**

(75) Inventor: **Jonathan Coudron**, Minneapolis, MN (US)

(73) Assignee: **Search Results, LLC**, Minneapolis, MN (US)

(**) Term: **14 Years**

(21) Appl. No.: **29/406,191**

(22) Filed: **Nov. 10, 2011**

(51) LOC (9) Cl. **32-00**

(52) U.S. Cl.

USPC **D14/486**

(58) **Field of Classification Search**

USPC D14/485-495; 715/700-867, 973-977

See application file for complete search history.

(57) **CLAIM**

The ornamental design for a tab area search tool for a display screen, as shown and described.

DESCRIPTION

A portion of the disclosure of this patent document contains material which is subject to copyright protection. The copyright owner has no objection to facsimile reproduction by anyone of the patent document or the patent disclosure, as it appears in the Patent and Trademark Office patent file or records, but otherwise reserves all other copyright rights whatsoever.

FIG. 1 is a view of a tab area search tool for a display screen, according to an example embodiment and showing my design.

FIG. 2 is a detail view of the tab area search tool for a display screen, showing a detail view according to an example embodiment and of my design; and,

FIG. 3 is a view of the tab area search tool displayed on a monitor, according to an example embodiment and showing my design.

Subject matter showing display screens, windows, content displayed in a web browser or other application is shown in broken lines for illustrative purposes only and forms no part of the claimed design.

1 Claim, 3 Drawing Sheets

FIG. 1

FIG. 2

FIG. 3
